UNITED STATES PATENT OFFICE.

CHARLES A. JUENGST, OF CROTON FALLS, NEW YORK.

STAPLED SIGNATURE FOR BOOKS.

No. 893,511.

Specification of Letters Patent.

Patented July 14, 1908.

Application filed December 9, 1907. Serial No. 405,684.

To all whom it may concern:

Be it known that I, CHARLES A. JUENGST, a citizen of the United States, residing at Croton Falls, in the county of Westchester 5 and State of New York, have invented an Improvement in Stapled Signatures for Books, of which the following is a specification.

In the art of book-binding it is common to 10 sew the signatures through the back and then together, and it is also common to secure the signatures together by staples or wires passed through the mass of signatures sidewise. This latter is especially true of a 15 limited number of signatures forming a pamphlet. Books made in this manner will not open out flat and this is especially true of those where the signatures are held by staples.

20 My invention relates to a group of stapled signatures ready to be put into a cover to form a book, and the object of my invention is the production of a book of collated stapled signatures capable when open of lying 25 out flat.

In carrying out my invention the signatures composing the book and connected together are connected together by staples bridging over the backs of the signatures, 30 with one end of a staple entering through the back of one signature and the other end of the staple entering through the back of the next adjacent signature and the respective free ends within the signatures bent toward 35 the body of the staple.

The various staples holding together the respective signatures for each book are set in a staggered relation to one another, so as to avoid the increase of thickness that would 40 arise if the staples were all set in line, but I do not limit myself to any particular arrangement of staples for thus connecting the signatures.

In the drawing, Figure 1 is a perspective 45 view looking at the back of a number of connected signatures, showing the device of my improvement. Fig. 2 is a broken or detached plan showing a portion of adjacent signature backs in large size and with a 50 staple in position. Fig. 3 is a cross section at the dotted line x, x , of Fig. 2. Fig. 4 is a plan showing part of a signature thus stapled as opened out. Fig. 5 is an end elevation of the signatures as shown in Fig. 4, showing 55 the flat opened out position assumed by a

number of connected signatures and Fig. 6 is a broken plan showing a form of my invention.

Referring particularly to Fig. 1, $a a^1 a^2 a^3 a^4 a^5 a^6 a^7$ represent the respective signatures as connected together by staples. b represents the respective staples and $b^1 b^2$ the free ends of each staple. As will appear especially from Figs. 1 and 2, the respective staples are placed diagonally, bridging or 60 extending across between the central portions of the backs of adjacent signatures with their free ends entering the backs of the adjacent signatures; the free ends b^1 and b^2 of the staple being bent toward the body 70 member and toward the opposite end of the next staple which according to Fig. 4, appears at the center of a signature when it is laid open. I aim also to prevent the accumulated thickness of the book of signatures 75 by staples placed in this manner, and to that end prefer to stagger the various staples with relation to one another as will particularly appear by reference to Fig. 1. In this manner the inturned free ends of one staple do 80 not come into opposition with the inturned ends of the next adjacent staple, consequently there is ample room for the inturned ends without coming into transverse contact or close relation with one another; this 85 would increase the thickness of the book and also the compression against the paper which would tend to cut the same.

Where two inturned ends of the staples in line are separated by the thickness of two 90 signatures and come into every third signature there is always room to accommodate these ends and this condition will be apparent from Fig. 1 of the drawing.

As shown in Fig. 1, the centrally placed series of staples run in the opposite direction to those of the end series. The essential object in thus running the staples of the series in opposite directions, viz: to prevent the staples of the series acting as hinges and permitting the swinging and consequently opening out of the signatures as would be the case if they all ran in the same direction.

In the form of my invention shown in Fig. 6, the staples c bridge directly across the backs of the signatures $a a^1 a^2$ and enter adjacent signatures with the free ends of the staples turned along in the folds of the signatures in opposite directions; therefore I do not in any respect limit myself to the arrange- 110

ment of the staples across the backs of the collated signatures.

I claim as my invention:

1. A series of signatures and a series of staples connecting the same for binding, each staple bridging directly over the folds from one signature to another, with the free ends of a staple entering the signatures and turned over.
2. A series of signatures and a series of staples connecting the same for binding, each staple bridging diagonally over the back from one signature to the next, with the free ends of the staple entering the adjacent signatures and turned over.
3. A series of signatures and a series of staples connecting the same for binding, each staple bridging diagonally over the back from one signature to the next adjacent signature, with the free ends of the staples passing centrally into the folds of the adjacent signatures and turned over to lie closely within the folds of the signature.
4. A series of signatures and a series of staples connecting the same for binding, each staple bridging diagonally over the back from one signature to the next adjacent signature, with the free ends of the staples passing centrally into the folds of the adjacent signatures and turned over to lie closely within the folds of the signatures and said staples set in a staggered relation one to another so as to avoid the increase of thickness that would arise if they were set in line.
5. A series of signatures and groups of staples in series connecting the same for bind-

ing, each staple bridging diagonally over the back from one signature to the next adjacent signature, with the free ends of the staples passing centrally into the folds of the adjacent signatures and turned over to lie closely within the folds of the signatures, with the staples of each series running in like direction and the staples of one series running in a direction which makes with the lines of the back folds of the signatures an angle equal and opposite to that of the staples of the other series.

6. A series of signatures and three groups of staples connecting the same for binding, one of the groups being central in the length of the folded backs of the signatures and the other two groups being adjacent to the ends of the folded backs, the staples of the end groups inclined alike and running in the same direction diagonally and the staples of the central group running in a direction which makes with the line of the back folds of the signatures an angle equal and opposite to that of the staples of the other series, and every staple bridging diagonally over the back from one signature to the next adjacent signature, the free ends of the staples passing centrally into the folds of the adjacent signatures and turned over to lie closely within the folds of the signatures.

Signed by me this 2d day of December, 1907.

CHAS. A. JUENGST.
